UNITED STATES PATENT OFFICE.

ADOLF P. LINK, OF BROOKLYN, NEW YORK.

BURNER.

1,115,845.

Specification of Letters Patent.

Patented Nov. 3, 1914.

Application filed July 26, 1912. Serial No. 711,616.

To all whom it may concern:

Be it known that I, ADOLF P. LINK, citizen of the United States of America, residing at Brooklyn, New York, have invented certain new and useful Improvements in Burners, of which the following is a specification.

My invention relates generally to hydro-carbon burners, and has especial reference 10 to heaters adapted for burning oils of practically any specific gravity.

One object of the invention is to provide a simple form of burner which may be cheaply constructed to economically and 15 noiselessly burn oils, greatly varying in specific gravity, with an intensely hot flame.

A further object is to provide effective means, in a burner of this character, for preventing carbonization of the fuel on the 20 walls of the container therefor.

A further object is to avoid the necessity 25 of providing means extraneous to the burner to furnish an adequate air supply or draft, and to so construct the burner that it will be self contained and embody in its structure means which may be increased or decreased as desired for supplying as abundant an air supply as if an external forced draft were present.

30 A further object of the invention is to provide means in a burner of this type for containing a liquid which performs the triple function of preventing carbonization of the fuel on the walls of the fuel container, assisting in vaporizing or comminuting the fuel, and in creating a draft to furnish an adequate supply of air to form the combustible mixture.

35 A further object is to provide simple 40 means for feeding fuel and liquid to, and draining the same from, the burner.

A still further object of the invention 45 is to provide means in the air tubes or passages for preventing the drip on to the ground or floor of any oil which may overflow from the oil container or escape through the jet tubes of the burner.

Other objects and advantages of the invention, and its structure and operation 50 will be clearly disclosed in the following description, reference being had to the accompanying drawing, wherein—

55 Figure 1 is a substantially central vertical sectional view of a burner embodying my invention; Fig. 2 is a horizontal sectional view on the line 2—2 of Fig. 1; Fig. 3 is a

vertical sectional view of a modification; Fig. 4 is a detail view of a jet nozzle.

In one practical embodiment of the invention I employ a suitably formed casing 60 open at the top and comprising the base 10 and lateral wall 11. The casing may be made in any desired shape, but I have found a cylindrical casing to be best adapted for the purpose and have so illustrated it in 65 the drawing. Projecting through the base 10 into the interior of the casing is a preferably frusto-conical central air tube or duct 12 the smaller end of which opens into the casing substantially at a point in line 70 with the median part of the wall 11. At its lower end this duct is preferably inwardly curved or turned, as at 12^a, for a purpose to be later explained. Arranged concentrically about the central tube 12 is a 75 substantially annular air conduit 13, of frusto-conical formation, the lower walls of the conduit 13 being flared and at their inner surfaces contacting with the lower outer surfaces of the central tube. By this 80 arrangement the least possible obstruction to the admission of air is presented. The lower edges of the walls of the conduit 13 are inturned at 13^a.

Arranged substantially in line with the 85 top of the air tube 12 and the conduit 13 is a series of orifices 14 formed in the casing wall 11, these orifices being preferably of angular elongated formation to present as great an area as possible for admission of 90 atmospheric air to the interior of the burner at this point.

The hydrocarbon (oil) containing means 95 may be of any suitable construction, and for my purpose I have found the form clearly shown in Fig. 1 to be most effective. This form of oil container includes a tray or receptacle 15, provided with a depression 16 which serves as the oil container proper. The lateral wall of each oil container is 100 preferably slightly inclined so as to make the container somewhat conical, and the container itself is annular in form, surrounding and snugly resting against the exterior surfaces of the air tube 12 and the 105 conduit 13. The upper edge 16^a of the oil container wall is turned substantially at a right angle to the lateral wall so that this upper edge may engage and remain tightly in contact with the outer surface of the 110 walls of the air tube 12 and conduit 13.

To secure the oil containers in position I

provide the bolts 17 passing through the container base and the casing base, and the winged nuts 18 for engaging the threaded ends of the bolts. Extending from the walls 16^a of the oil containers is a series of jet tubes or nozzles 19 inclined in the direction of the containers 16 and openings 14 the mouths or emission openings of said nozzles being substantially elliptical in 10 shape. The base of the containers 16 is spaced away from the base 10 of the casing so as to form a chamber 20 to receive water or any other readily vaporizable liquid 21.

I preferably provide inner and outer 15 concentric trays or oil containers 15, each having an oil containing depression 16. The depression in the inner tray is provided with oil in any suitable manner, as by pouring the oil into the depression, while the outer oil 20 containing depression 16 has an orifice 22^a in its vertical wall which is in communication with the open end of a pipe 22 leading to a source of oil supply (not shown). The pipe 22 is provided with a gage 23 to show 25 the level of oil in the outer container 16, and also has a cock 24 for governing the flow of oil into and out of the said outer container 16. The chamber 20 in the casing 10 is in communication with a suitable 30 source of water supply (not shown) by means of the pipe 25, provided with the gage 26, and having the siphon 27 and the valve 28, the latter operating substantially 35 in the same manner as the valve 24 in the oil pipe 22.

The air tube 12 and conduit 13 are internally ribbed, the ribs 29 being inwardly projecting to impede the downward passage 40 of any oil which may overflow from the burner.

Suitably supported over the upper openings in the central air tube and the concentric conduit are hoods or deflectors 30 which are both centrally and laterally 45 curved so as to deflect air entering through the tube 12 and the conduit 13 to both sides of the hoods and over the fuel in the containers 16.

The modified form of the invention shown 50 in Fig. 3 differs from the preferred form in having a baffle wall 31 of fire brick or the like so arranged above the burner that, if the rising vapor is charged with liquid or non-vaporized particles, the heat of the wall 55 31 will tend to vaporize such particles. The wall 31 is provided with the transverse openings 32 and is secured to the burner at its upper edge, as shown.

My invention is applicable to numerous 60 uses, but it is especially designed for, and has been found to be thoroughly efficient as, a heater for boilers employed for domestic purposes. Assuming the heater to be constituted as shown in the drawing and to be 65 installed under the ordinary domestic water

boiler the operation is as follows:—Water is permitted to flow into the space 20, and thereafter oil in suitable quantities is permitted to flow into the containers 16, and the oil is ignited by a piece of burning waste 70 or the like causing the water to boil. The heat of the boiling water transmitted through the lateral walls of the container 16 will cause vapor to arise from the oil, and this vapor, which mixes with steam coming 75 through the jets 19 and air issuing through the tube 12 the conduit 13 and the openings 14 forms a highly combustible mixture which, when once ignited by a flame within the burner, sustains combustion as long as 80 oil is fed to the oil containers. The baffle plates 30 will direct the air coming through the tube 12 and the conduit 13 over the oil containers, the openings 14 will also direct the air over the containers, and the jets 19 85 will have a like effect on the steam, these several instrumentalities acting in the nature of a Bunsen burner, directing toward each other steam and air which mixes with hydrocarbon vapor, forming two streams which 90 then spread out and burn with an intensely hot flame. The forcible issuance of the steam through the jets tends to create a vacuum in the burner whereby air will be 95 forcibly sucked in through the tube 12, conduit 13 and openings 14, which action will be in the nature of a forced draft, thus providing for an abundant supply of air, under all conditions, to the mixture. Should there be any oil overflow either from the containers or by vapor condensation, and the 100 overflow pass down through the tube 12 and conduit 13 the ribs 29 will retard the flow and as the tubes are fairly hot any such overflow will vaporize before it reaches the 105 lower end of the tubes and conduit. If, however, all the overflow should not so vaporize the inturned edges of the tube and conduit will act as a drip pan and prevent the oil from falling to the floor. If particularly 110 heavy oils are to be used, I employ the modified form of Fig. 3, the baffle wall 31 acting as a heat vaporizer for any liquid particles carried upward by the vapor. When the 115 action of the heater is to be stopped the oil supply is shut off and the cock 24 opened to drain the oil out of the containers 16. Thereafter the water, may, if desired, be drained out of the space 20. Owing to the presence of the boiling water in contact with the oil containers 16, all the oil will be 120 vaporized and no carbonization on the inner walls of these containers will take place.

Despite the strong draft in the burner, due in part to the action of the steam, I have 125 found that in operation the burner is practically noiseless which is a great desideratum and the accomplishment of which has been attempted, but unsuccessfully I believe, in numerous instances. It will also be under- 130

stood that the tray or receptacle is removable as a whole, so that ready access may be had to the interior of the burner for cleaning and other purposes.

5 5 I claim—

1. A burner of the character specified, embodying therein a plurality of concentrically arranged air admission means, means surrounding said air admission means for receiving vaporizable fuel, and means for directing a plurality of jets of vapor into the path of the vapor issuing from said fuel.
- 10 2. A burner of the character specified, embodying therein a plurality of concentrically arranged frusto-conical air admission means, means surrounding said air admission means for receiving vaporizable fuel, and means for directing a plurality of jets of vapor into the path of the vapor issuing from said fuel.
- 15 3. A burner of the character specified, embodying therein a casing having a chamber designed to receive a vaporizable liquid, a plurality of concentrically arranged air admission means opening into the casing, fuel receiving means surrounding said air admission means, and means for directing the vapor issuing from the liquid into the path of the vapor issuing from the fuel.
- 20 4. A burner of the character specified, embodying therein a casing, air admission means opening into said casing, said air admission means including a central tube or duct and an annular conduit concentric therewith, fuel containers adjacent said means, means for deflecting air passing through said air admission means over the fuel containers, and means for vaporizing said fuel.
- 25 5. A burner of the character specified, embodying therein a casing, a plurality of spaced, concentrically arranged air admission means opening into said casing, fuel containers engaging said air admission means and spaced away from the casing to form a chamber below said containers for receiving vaporizable liquid, and means for directing the vapor issuing from said liquid over said fuel containers.
- 30 6. A burner of the character specified, embodying therein a casing, a plurality of spaced, concentrically arranged air admission means opening into said casing, a tray having fuel receiving depressions therein, the lateral walls of said depressions being adapted to engage said air admission means, and means whereby vapor from a liquid is directed in a plurality of fine streams into the path of the vapor issuing from the fuel in said depressions.

- 35 7. A burner of the character specified, embodying therein a casing having orifices in its lateral wall, a plurality of air admission means having one end of each opening into the casing substantially in line with said

orifices, air admission means including a central tube and an annular conduit concentric therewith and fuel containing means having open ends substantially in line with said orifices and the said ends of the air admission means.

8. A burner of the character specified, embodying therein a casing, air admission means opening into said casing, fuel containers supported by said air admission means, there being a liquid chamber between the base of the casing and the lower surface of said fuel containers, deflectors over said air admission means to deflect the air issuing therefrom over the fuel containers, and means for directing vapor issuing from said liquid chamber over said fuel containers.

9. A burner of the character specified, embodying therein a casing having a series of orifices in its lateral wall, a plurality of air admission means having one end of each opening into said casing at a point substantially in line with said orifices, fuel containing means having one end open and substantially in line with said orifices and said ends of the air admission means, and deflectors over said last named means for directing air issuing from the latter over said fuel containing means.

10. A burner of the character specified embodying therein a casing having a series of orifices in its lateral wall, frusto-conical air admission means having reduced ends opening into the casing at points substantially in line with said orifices, fuel containers engaging said air admission means and having their lower surfaces spaced away from the base of the casing to form a liquid chamber, each of said containers having an open end substantially in line with said orifices, and jet tubes adapted to direct vapor issuing from said liquid chamber to mix with the air entering said casing and with the vapor arising from the fuel in said containers.

11. A burner of the character specified, embodying therein a casing having a series of orifices in its lateral wall, a plurality of air admission means having one end of each opening into said casing, said air admission means including a central tube or duct and an annular conduit concentric therewith, and a tray within said casing and having fuel containing depressions the lateral walls of which engage the walls of the air admission means.

12. A burner of the character specified, embodying therein a casing having a series of orifices in its lateral wall, a plurality of air admission means having one end of each opening into said casing at a point substantially in line with the said orifices, a tray within said casing and having a fuel containing depression therein the lower sur-

face of which is spaced away from the base of the casing to form a liquid chamber, and means for directing vapor issuing from said liquid chamber over the open end of said fuel containing depression.

13. A burner of the character specified, embodying therein a casing having a series of orifices in its lateral wall, internally ribbed air admission means opening into said casing, deflectors arranged over the ends of said air admission means which open into the casing, a tray within said casing having a fuel containing depression therein the lateral walls of which engage the walls of the air admission means, there being a liquid chamber between the lower surface of said depression and the base of said casing, jet pipes for directing vapor from said liquid chamber over said fuel containing depression, means for supplying liquid to and draining the same from said liquid chamber, and means for supplying fuel to and draining the same from said fuel containing depression.

25 14. A burner of the character specified, embodying therein a casing, a frusto-conical air admission tube having the reduced end thereof opening into said casing substan-

tially at its central part, an annular frusto-conical air admission conduit having the reduced end thereof opening into said casing and its flaring end contacting with the flaring end of said tube, and a fuel container arranged within said casing and spaced away from the base of the casing to form a chamber for receiving vaporizable liquid.

15. A burner of the character specified, embodying therein a casing having a series of orifices in its lateral wall, a refractory baffle wall arranged over said casing, air admission means opening into said casing, fuel containers engaging said air admission means and having their lower surfaces spaced away from the base of the casing to form a liquid chamber, means for supplying liquid and fuel to said burner, and means for directing vapor issuing from the liquid in said liquid chamber into the path of the vapor issuing from the fuel in said fuel containers.

In testimony whereof I have affixed my signature in presence of two witnesses.
